UNITED STATES PATENT OFFICE.

EDGAR VINCENT CHAMBERS, THOMAS CHARLES HAMMOND, AND GEOFFREY G.
JARMAIN, OF HUDDERSFIELD, ENGLAND.

PROCESS FOR THE CONCENTRATION OF WOOL-SCOURING AND LIKE LIQUORS AND THE RECOVERY OF GREASE AND ALKALINE SUBSTANCES THEREFROM.

1,170,962.

Specification of Letters Patent.

Patented Feb. 8, 1916.

No Drawing.

Application filed May 10, 1915. Serial No. 27,077.

To all whom it may concern:

Be it known that we, EDGAR VINCENT CHAMBERS, THOMAS CHARLES HAMMOND, and GEOFFREY GEORGE JARMAIN, subjects of 5 King George V of Great Britain, residing at Huddersfield, in the county of York, England, have invented certain new and useful improvements in processes for the concentration of wool-scouring and like liquors 10 and the recovery of grease and alkaline substances therefrom, of which the following is a specification.

This invention relates to the concentration of wool scouring and like liquors and 15 the recovery of grease and alkaline salts or substances contained therein and has for its object the treatment by an improved process of such scouring liquors for the purposes specified and for admitting of re-use 20 of the scouring liquor after each separation has been effected, such improved process eliminating the purification of polluting effluent heretofore required before its discharge into the river and the use of acid 25 necessary for recovering grease by other processes, and effecting a considerable saving of soap and alkaline detergents.

For effecting an easy separation of grease from scouring liquor, it is necessary to obtain 30 as great a difference of density between the grease and the aqueous portion of the liquor as possible, and previously this has best been obtained by evaporation of 35 the scouring liquor after it has been once used in the scouring machine. This process of evaporation necessitates the employment of a costly plant, which has frequently to be repaired and a considerable expenditure in fuel, while close attention must be given 40 during the operation.

Our invention is intended to obviate the necessity for evaporation and in carrying out our improved process, we take the liquor from the scouring machine or vessel, 45 when it has become foul, and subsequently separate the sand contained therein by settlement and remove the fiber therefrom by screening by any approved means. The effluent when it has thus been treated is heated 50 to a temperature of about 200° F. and conveyed into a centrifugal separator acting on the principle of centrifugal force whereby the grease is separated from the

liquor and is removed from the inner layer or surface by a skimming pipe or pipes in 55 known manner, while the liquor, which forms the next layer, and is freed from surplus grease, is in a suitable condition for re-use as a scouring agent and is conveyed back to the scouring machine, the residue 60 of the sand left in the liquor forming a third layer against the inner wall of the basket or drum of the extractor from which it is subsequently removed by hand or other means. The object of heating the liquor to 65 about the boiling point of water is to prevent bacterial decomposition, and to raise the grease or lanoline to a temperature above its melting point, so that the anhydrous lanoline may be recovered by the centrifugal 70 separator. This operation is repeated, each time the scouring liquor becomes foul, as many times as may be necessary until said liquor becomes more or less saturated 75 with alkaline salts naturally occurring in the wool fiber, and when a certain suitable density has been attained, this varying with the quality of the wool passing through the machine and being determined by the physical characteristics of the liquor which on 80 becoming thick and viscous is unsuitable for wool scouring, the liquor is again returned to the centrifugal machine for the final removal or separation of the grease and the cleared liquor is afterward incinerated 85 in any suitable type of incinerator, whereby the potash and soda, if present, are recovered in the dried state.

The above process of repeated subjection of the liquor, when foul, to heating and centrifugal action effects the desired concentration without the necessity of evaporation and therefore effects a considerable economy in soap and other detergent materials necessary in the scouring process. It 90 will also be understood that the use of acid for the recovery of grease is eliminated. By repeated use of the liquor as above set forth, the separation becomes fully effective.

Where evaporation has not been performed, the foul liquor has formerly been screened to recover the fiber and then discharged direct into the river, or into a purification plant, in either case this necessitating a fresh bath with a fresh supply of soap and soda.

In our process the soap and soda are not discharged by centrifugal treatment of the liquor but remain in the liquor after separation of the grease so that the liquor on return to the scouring machine requires no further addition of soap and soda excepting such as may be necessary at any time to make up for any loss by usage and therefore the consumption of such substances is minimized and a considerable economical advantage obtained. Further, the foul liquors being returned for re-use after each treatment by our process, no purification process is called for and there is no discharge of scouring liquor into the drain or river. The recovery of wool fat from washing liquors by treating the liquor in a centrifugal extractor has been previously proposed and no broad claim is made thereto *per se.*

In the process of concentration according to our invention, it may possibly occur that the scouring liquor is unsuitable for scouring purposes by reason of its high content of alkaline salts while at the same time this concentration may not be considered sufficiently suitable for incineration. Under these circumstances, we propose to treat the scouring liquor with washed flue gases which maintain said liquor in suitable efficiency and enable more complete concentration to be obtained, said flue gases being forced through the liquor or the liquor allowed to trickle down a flue up which the washed gases are passed. The period of carbonation is determined by the physical state of the liquor which becomes so slippery in working that the wool fails to pass through or between the rollers.

Having thus described our invention,

what we claim as new and desire to secure by Letters Patent is:—

1. A process for the treatment of foul scouring liquor, which consists in heating the foul liquor so as to liquefy the grease in it, and then subjecting the hot liquor to centrifugal action to separate the grease from the liquor leaving the liquor freed from surplus grease and in suitable condition for re-use as a scouring agent. 50

2. A process for the treatment of foul scouring liquor, which consists in first permitting the sand and heavy particles to settle by gravity, decanting the liquor and screening it to remove fibers, then heating the foul liquor so as to liquefy the grease in it, and then subjecting the hot liquor to centrifugal action to separate the grease from the liquor leaving the liquor freed from surplus grease and in suitable condition for re-use as a scouring agent. 55

3. A process for the treatment of foul scouring liquor, which consists in heating the foul liquor to liquefy the grease in it, then subjecting the hot liquor to centrifugal action to separate the grease from it without removing the soap and alkali, and finally removing any deleterious excess of alkali from the liquor by subjecting it to the action of a suitable reagent to effect carbonation. 65

In testimony whereof we affix our signatures in the presence of two witnesses.
